R. S. ELLIS

CONCRETE STRUCTURE

Filed Dec. 31, 1924

UNITED STATES PATENT OFFICE.

RUSSELL SCOTT ELLIS, OF PHILADELPHIA, PENNSYLVANIA.

CONCRETE STRUCTURE.

Application filed December 31, 1924. Serial No. 759,207.

My improvements are designed and adapted to facilitate the sinking of concrete or other structures by means of water jetting, and are particularly adapted for installing 5 such structures in sandy soil.

As hereinafter described, my invention includes the provision of a base member primarily separate from, but adapted to be readily attached to, a pile of concrete or 10 wood or other material of such form, construction and arrangement as to facilitate the use of water to sink the columnar member to which it is attached and to facilitate the gravitation of the latter.

15 As hereinafter described; my improved base member may be formed of concrete molded in a pyramidal form, imbedding a water jet tube extending from the apex of the pyramid, which is used up side down, to an upper corner thereof, and having a bayonet slot or other detachably connecting 20 means for temporarily engaging a water supply conduit, and also having imbedded therein, flexible metal hangers having their free 25 ends projecting therefrom, primarily in such position that the lower end of the columnar member may be readily inserted between said hangers; the latter being then bendable to then engage metal studs or hooks 30 projecting from the columnar member; whereby, such a base member may be permanently attached to a columnar member and form a footing for the latter after it has been sunk in the soil. My invention includes 35 an improved suspension clamp which supports said water conduit and is provided with means for detachably connecting it with the columnar member; whereby the latter may be suspended, lifted and lowered, as 40 hereinafter described.

My invention includes the various novel features of construction, arrangement and procedure hereinafter more definitely specified.

45 In the drawings: Fig. I is a fragmentary side elevation of a columnar member and suspension clamp carrying an adjustable water conduit embodying my invention.

Fig. II is a plan view of the suspension clamp and its appurtenances shown in Fig. I.

Fig. III is a side elevation of a base member in position to receive said columnar member and conduit shown in Fig. I.

Fig. IV is a plan view of said base member, as shown in Fig. III.

Fig. V is a fragmentary side elevation of said columnar member and conduit shown in Fig. I, with the base member shown in Fig. III connected therewith.

Fig. VI is a plan view of the assembled 60 parts shown in Fig. V.

In said figures; the base member 1 is conveniently formed of a concrete aggregate, or other plastic material, molded or cast in pyramidal form, imbedding the water jet tube 65 2 having its lower end 3 extending from the apex of the pyramid and having its upper end 4 projecting from an upper corner of said base. As indicated in Figs. III to VI inclusive; said jet tube end 4 carries a cross 70 bar 6 forming detachably connecting means for temporarily engaging the opposite bayonet slots 7 in the water supply conduit 8, as shown in Fig. V. Said base also has imbedded therein a circular series of flexible 75 metal hangers 10 having their lower ends 11 bent toward each other, for better engagement with the material of said base 1 and having their free ends projecting therefrom primarily in such position, as exemplified in Fig. III, that the lower end of the columnar member 12 may be readily inserted between said hangers. Each of said hangers has a perforation 13, near its upper end, adapted to register with metal studs 14 which 80 are imbedded in and project from said columnar member 12 and both said hangers and said studs are bendable to interengage them as indicated in Fig. V; whereby such a base member 1 may be permanently attached to 85 such a columnar member 12.

I find it convenient to reinforce said base member 1 by an annular member 16, conveniently formed of a steel bar, encircling the lower ends of said hangers. However, other 90 reinforcing means may be employed.

Said columnar member 12 is indicated as a molded concrete pile or column provided with metallic reinforcements including longitudinal members 17 encircled by transverse 100 annular members 18. However, I do not desire to limit myself to such construction, as my invention is, of course, applicable to piles or columns of wood or other material.

I find it convenient to suspend the conduit 8 and columnar member 12 by means of a suspension clamp conveniently consisting of a metal plate 20 having the bearing 21 for said conduit 8 and provided with the swivel suspension eye 22 for engagement with 110

the suspension cable 23. Said plate 20 includes the downwardly bent portion 24 serving as an abutment for one side of the columnar member 12 and opposed by the U-bolt 5 25 which has its opposite ends extending through holes 26 in said plate 20 and provided with nuts 27. The U-bolt 29 is hingedly connected with said plate 20 by bearings 30 and has its opposite free ends extending 10 through the yoke bar 31 and provided with nuts 32; whereby said bolt 25 may be clamped toward the pendent portion 24 of said plate 20 to grip the upper end of said columnar member 12 so that it may be raised, 15 suspended and lowered by manipulation of the cable 23.

Said conduit 8 is provided with the clamp bearing 34 for the hand lever 35 which may be supplemented by the removable tubular extension 36; whereby said conduit may be raised and lowered and turned. As shown in Fig. I; the bayonet slots 7 in the lower end of said conduit 8 are in alinement with the cross bar 6 in the upper end 4 of the water jet tube 2, so that when said conduit is lowered into said tube end 4, it may be engaged therewith by turning said lever 35 in the direction of the arrow indicated in Fig. II. Said lever extension 36 is provided with 30 the flexible connector 37 for detachable connection with the projection 38 on said plate 20; whereby said conduit 8 may be detachably detained in interlocked engagement with said cross bar 6 of said jet tube 2.

35 The apparatus above described may be used as follows: The suspension clamp including said plate 20, is fitted to a selected columnar member 12, as indicated in Fig. I; and firmly secured thereon by tightening the nuts 32. Said columnar member 12 is then provided 40 with a base member 1 fitted thereon to the position shown in Fig. V, and with the conduit 8 in connection with the jet tube 2, as indicated in that figure. Thereupon, water under pressure may be supplied through said conduit 8 to displace the sandy soil 40 beneath said base 1 while the latter and the columnar member 12 connected therewith are lowered by slackening the cable 23. Such operation is 45 continued until the columnar member 12 has sunk to the desired position. Thereupon, the flexible connector 37 is disengaged from the projection 38 and said hand lever 35 turned in the direction opposite to the arrow in Fig. II, thereby returning the conduit 8 to the position shown in Fig. I in which it may be withdrawn upwardly from the upper end 4 of the jet tube 2 by means of the suspension clamp plate 20 which is released from 50 the columnar member 12 by reverse rotation of the nuts 32 so that the suspension clamp may be uplifted by the cable 23 and applied to another columnar member, and the operation repeated.

60 65 So far as I am aware, it is original with

myself to provide a base member, of the generic character above described, to facilitate the use of water to sink columns of piles and to form a permanent footing for the members thus sunk. Therefore, I do not desire to limit myself to the precise details of construction, arrangement and procedure herein set forth, as it is obvious that various modifications may be made therein without departing from the essential features of my invention, as defined in the appended claims. 70 75 80

I claim:

1. A base member for a columnar element arranged to facilitate sinking thereof by water jetting and adapted to form a permanent footing for said element, including a molded concrete body of pyramidal form having a metallic water jet passageway imbedded in said concrete and extending from the apex thereof to a corner thereof; and means arranged to attach said base member to said columnar element, including an annular series of flexible metal hangers projecting from said base member, and each having one end imbedded in said concrete; and an annular metallic member also imbedded in said concrete and interlocked with the ends of said hangers. 85 90 95

2. A base member for a columnar element, including a body formed of concrete molded in a pyramidal form, imbedding a water jet tube extending from the apex of the pyramid to a corner thereof; said corner end of said tube having bayonet slot connecting means arranged to temporarily engage a water supply conduit; said body having imbedded therein flexible metal hangers having free ends projecting from the surface thereof opposite to said apex; said free ends being perforated and arranged to engage lateral projections extending from said columnar element; whereby said base member may be permanently attached to a columnar element to facilitate sinking thereof by means of water jetting and to form a footing for said element 100 after it has been sunk. 105 110

3. The combination with a columnar element having lateral projections adjacent to the lower end thereof; of a primarily separate precast base member comprising a concrete body of pyramidal form having metallic hangers projecting therefrom and primarily detached from, but arranged to permanently engage the projections on said columnar element; and said base having a metallic water jet tube imbedded therein extending from the apex to one corner thereof; and said tube having means arranged to detachably connect it with a rotary water conduit. 115 120 125

4. The combination with a base of downwardly converging form having a water jet passageway from its lower apex to its upper surface; of a water conduit having means arranged for detachable connection with said base and passageway; and an adjustable sus- 130

pension clamp including a bearing support for said conduit, arranged to permit rotary and axial movement of said conduit therein and screw bolts arranged to detachably clamp 5 a columnar element in cooperative relation with said conduit and base; and means cooperatively connecting said conduit and clamp, whereby they may be applied and removed to-

gether, with respect to said columnar element.

In testimony whereof, I have hereunto signed my name at Philadelphia, Pennsylvania, this twenty-seventh day of December, 1924.

RUSSELL SCOTT ELLIS.
